United States Patent

Des. 240,598
Patented July 20, 1976

240,598

STUD SETTER

Harold Isaacs, 2750 Homecrest Ave.,
Brooklyn, N.Y. 11235

Filed Feb. 18, 1975, Ser. No. 550,819

Term of patent 14 years

Int. Cl. D8—05

U.S. Cl. D8—47

FIG. 1

FIG. 4

FIG. 2

FIG. 3

FIG. 1 is a side elevational view of a stud setter showing my new design;

FIG. 2 is a top plan view thereof;

FIG. 3 is a sectional view taken on the line 3—3 of FIG. 2; and

FIG. 4 is a sectional view taken on the line 4—4 of FIG. 1.

I claim:

The ornamental design for a stud setter, substantially as shown.
